(57) **CLAIM**

The ornamental design for a safety vest with a light tube as shown and described.

DESCRIPTION

FIG. 1 is a perspective view of the rear of a safety vest with a light tube;

FIG. 2 is a perspective view of the rear of the safety vest with a light tube from an upper angle;

FIG. 3 is a front view thereof;

FIG. 4 is a rear view thereof;

FIG. 5 is a side elevation view thereof from the left side;

FIG. 6 is a side elevation view thereof from the right side; and,

FIG. 7 is a perspective view of the front thereof from a lower angle.

The broken lines in the drawings showing the head, arms, and waist of a wearer in FIG. 1 depict environmental structure and form no part of the claimed design. The broken lines shown within the article depict stitching and other parts of the article that form no part of the claimed design.
